DIFFERENTIAL RATE HYDRAULIC FUSE

Chalmers A. Strayer, Torrance, Calif., assignor to Northrop Aircraft, Inc., Hawthorne, Calif., a corporation of California

Application December 18, 1953, Serial No. 398,945

6 Claims. (Cl. 60—52)

This invention relates to hydraulic fuses and more particularly to a hydraulic fuse adapted to detect leakages and arrest fluid flow to certain portions of a closed circuit continuous flow hydraulic system. The system with which the subject fuse is associated being further characterized in that return and supply flow is equal throughout the normal operation of the system.

A fuse of the type disclosed herein may be utilized to effectively arrest the flow of hydraulic fluid to a neutral leakage servo actuator of the type shown and disclosed in U. S. Patent No. 2,640,466. An actuator of this type being particularly adapted to operate the control surfaces of an aircraft.

In an aircraft of the aforementioned type, that is one having its control surfaces operated by hydraulic actuators positioned adjacent these surfaces, a plurality of hydraulic lines necessarily extend through the aircraft's fuselage and wings. These lines are susceptible to damage and resulting leakage of fluid therefrom due to natural causes and also enemy gunfire in the case of military aircraft. If such damage should occur to certain portions of an aircraft's hydraulic system it is important that means be provided to isolate these damaged portions and at the same time maintain undamaged portions in an operating condition.

Hydraulic fuses of various types have been utilized extensively to arrest fluid flow through a hydraulic system in response to fluid flow characteristics occurring therein at such time as they vary materially from normal operating characteristics. Fuses of the type referred to above generally are responsive to total fluid flow or rate of flow through a system. Fuses of this type will not, however, function to satisfactorily detect a leak from a continuous flow system under certain conditions. This is particularly true if the leak is of such small magnitude that it will not cause a greater flow through the system than the system is expected to carry during normal operating conditions. Such a condition may develop in the hydraulic lines conducting fluid to or from a servo actuator of the aforementioned type; a complete evacuation of the system may result if the leak is not detected and corrected immediately. While the fuse of the instant invention will detect a leak of small magnitude it will be equally effective in detecting and arresting fluid flow should a major fracture occur in the system.

An object of this invention is to provide a hydraulic fuse which may be easily installed at any point in a hydraulic system, the subject fuse functioning automatically to block fluid flow to certain portions of the system should a rupture occur therein.

2

Another object of this invention is to provide a hydraulic fuse which automatically functions to block fluid flow to certain portions of a hydraulic system with which it is associated at such times as differences occur in the fluid flow rate at identical sections in the pressure and return lines of the system.

Another object of this invention is to provide a hydraulic fuse which functions automatically to block fluid flow to certain portions of a hydraulic system with which it is associated, the fuse functioning when subjected to certain fluid conditions occurring within the system. The subject fuse automatically resetting itself at such times as the pressure of the entire system is reduced to atmospheric pressure thereby again providing a free course for fluid through the system.

Another object of this invention is to provide a hydraulic fuse which functions automatically to block fluid flow to certain portions of a hydraulic system in which it is installed when subjected to certain fluid conditions occurring therein. However the fuse will not block flow through the system due to temporary fluid surges occurring in the system.

These and other objects will become more apparent from the following description and drawings in which like reference characters denote like parts throughout the several views. It is to be expressly understood however, that the drawings are for the purpose of illustration only and not a definition of the limits of the invention, reference being had for this purpose to the appended claims.

In the drawings:

Figure 1 is a perspective schematic view of a hydraulic system utilized in an aircraft and includes a hydraulic fuse of the type disclosed in the instant invention.

Figure 2 is a sectional view of a preferred embodiment of the hydraulic fuse shown in Figure 1.

Figure 3 is a graphic representation of the fluid pressure drop which occurs as fluid flows through the fuse of Figure 2 at various flow rates.

Referring to the drawing for a detailed description of a preferred embodiment of the present invention, Figure 1 shows portions of an aircraft 10 in which the hydraulic fuse as disclosed herein is incorporated. In this figure hydraulic fluid under pressure is supplied to various servo actuators 11 (only one being shown) which are located in the outer extremities of the wings 12 and tail 14 to operate certain control surfaces of the aircraft, for example the left wing aileron 15.

Hydraulic fluid is circulated between a reservoir 17 and the actuators 11 through a plurality of hydraulic lines 50 comprising, a suction line 18, pressure lines 19 and 20, and return lines 21 by means of a pump 22. Positioned in the pressure and return lines 20 and 21 is a hydraulic fuse 23 through which fluid passes in flowing to and from the actuators 11. The pump 22 supplies fluid to the line 19 at a pressure of approximately 3000 p. s. i. The actuator 11 (described in the aforementioned U. S. patent) is of the neutral leakage type, accordingly fluid in the pressure and return lines is in a continuous and equal state of flow during all normal operating conditions of the system.

Referring now to Figure 2 for a detailed description of the hydraulic fuse 23 which comprises a body 24 provided with fluid inlets, outlets, internal chambers, and passageways for the flow of fluid therethrough. The fuse is provided with a first fluid inlet 25 located in an upper portion of its body (with the fuse positioned as shown in Figure 2), this inlet communicating externally with the discharge port of the pump 22 through the pressure line

19 and is, therefore, subject to the highest fluid pressure P_1 occurring in the system. A first fluid outlet 27 is provided in a lower portion of the body 24, this outlet communicates externally with the actuator 11 through a pressure line 20 and is subject to a fluid pressure P_2 . A second fluid inlet 28 is provided in a side portion of the fuse communicating externally with the actuator 11 and is subject to a fluid pressure P_3 . A second outlet 29, located in a lower portion of the fuse 23, communicates externally with the reservoir 17 and is subject to a fluid pressure P_4 . The pressure P_3 is normally very low with respect to pressure P_1 . Fluid pressure P_2 is slightly less than P_1 and P_4 is slightly less than P_3 , the reason for these pressure differentials and how they are achieved will become apparent as the disclosure progresses.

Located within the upper portion of the body 24 is a chamber 30 consisting of two cylindrical bores of different diameters but having a common axis. The chamber 30 is closed at one of its ends by wall portions of body 24 and at its other end by a plug 33. At approximately the mid-point of the chamber a valve seat 34 is provided, at this point the chamber is reduced in size to provide the aforementioned bores of larger and smaller diameters as indicated by numerals 35 and 37, respectively. The passage 25 provides fluid communication between line 19 and bore 35 of the chamber 30 at a point adjacent the valve seat 34.

Positioned within the bore 35 is a valve element 38 mounted for longitudinal movement therein. This valve element consists of a body portion 39, a conical portion 40, an extending end portion 42, and a counterbore 43 extending longitudinally within its body portion. The body portion 39 is of such configuration that it provides a sliding support for and maintains proper alignment of the valve element within bore 35 and at the same time allows fluid to completely surround the valve element. Positioned within the bore 37 is a piston element 45 consisting of a cylindrical body portion 47 and a projecting end 48 adapted to abut the end portion 42 of the valve element. The cylindrical surface of bore 37 and the cylindrical surface of the body portion 47 are lapped so that a minimum of fluid will leak past these mating surfaces. The valve element 38 and element 45 are urged into contacting relationship by a spring 49 positioned between the closed end of bore 37 and the adjacent end of element 45 and a spring 50 positioned in counterbore 43. The springs 49 and 50 are selected and preloaded so that elements 38 and 45 are caused to assume the position shown in Figure 2 at all times except when a failure occurs in hydraulic lines 20 or 21.

Also located in the body 24, below chamber 30, is another chamber 52 consisting of bores 53 and 54. Although the bores 53 and 54 are shown as having different diameters in the instant embodiment this need not necessarily be the case. These two bores are aligned so that they have a common axis which is parallel with the axis of chamber 30. One end of chamber 52 is closed by wall portions of body 24 and at its other end by a plug 57. Liners 58 and 59 are positioned in bores 53 and 54, respectively, and are located longitudinally in abutting relationship in these bores by means of suitable shoulders formed in the cylindrical walls thereof. The liners are further held in their respective positions by the plug 57. The end of liner 58, which abuts liner 59, is provided with an annular internal shoulder 60, its other end is similarly closed by a washer-like element 62 which is retained in position by the plug 57. Positioned within liner 58 is a piston assembly 63 adapted to move longitudinally therein. This assembly consists of a piston 64 and rod 65 the latter passing through central apertures formed in shoulder 60 and element 62. The plug 57 is counterbored to provide a fluid chamber 67 and also clearance for rod 65. A portion of rod 65 is reduced in cross-

sectional area as indicated at 68, this reduced portion extends longitudinally of rod 65 from a point adjacent piston 64 to a point short of its end portion. The purpose of the reduced portion 68 will be apparent presently.

5 The bore of liner 58 is divided into two chambers 69 and 70 by the piston 64.

Located in the bore of liner 59 is a piston 72 adapted to move longitudinally therein when subjected to certain fluid pressures. The piston 72 is maintained in contacting relationship with rod 65 by means of a helical spring 73 and divides the bore in liner 59 into two chambers 74 and 75. The cylindrical surfaces of pistons 64 and 72, both end portions of rod 65, and the surfaces with which they mate are lapped so that a minimum of fluid will leak past these surfaces. Suitable packing rings are provided in grooves formed in the outer cylindrical surfaces of liners 58 and 59 and between liner 58 and element 62 to preclude the escape of fluid at these locations. The diameters of the bores in liners 58 and 59 and the diameters of pistons 64 and 72 are equal.

10 Positioned in the fluid outlets 27 and 29 are identical poppet valves 77 which are adapted to move longitudinally in the outlets. These poppet valves have a cylindrical body portion 78 contacting the walls of outlets 27

15 and 29 and a conical portion 79 provided with an aperture 80 at the apex thereof. The valves 77 are urged into contacting relation with valve seats by means of springs 81, the aforementioned valve seats being formed by the intersection of the end surfaces of outlets 27 and 29 with the cylindrical walls of fluid passageways 82 and 83, respectively. The valves 77 may move in a downward direction (as viewed in Figure 2), at such times as fluid pressure acting thereon overcomes the force exerted by the springs 81, until they bottom on annular elements 84 retained in the outlets by expansion rings 86. The poppet valves are concentrically counterbored as indicated at 85 to provide suitable seats for one end of the helical springs 81. Extending through the conical wall portion of each poppet valve is a plurality of apertures 87 which provide unrestricted fluid communication between the interior of the outlet passages 27 and 29 and fluid passages 89 and 91, respectively. The function of the valves 77, apertures 80 and 87, and springs 81 will become apparent at such time as the operation of the fuse is explained.

20 The aforementioned passage 82 provides fluid communication between the outlet 27 and chamber 69. The passage 82 also is in fluid communication with the bore 37 of chamber 30 through a passageway 88. Fluid communication is also provided between outlet 27 and chamber 70 through passage 89. This latter passage is provided with a restrictor 90 which restricts the flow of fluid from chamber 70 for a purpose which will be explained later. The aforementioned passage 83 provides fluid communication between inlet 28, outlet 29, and chamber 67. Additional passages in the body 24 provide fluid communication between various chambers and aforementioned passages as follows: passage 92 extending between passage 83 and chamber 75, passage 93 between chamber 70 and bore 37, and a passage 91 between outlet 29 and chamber 74. Passage 93 communicates with bore 37 and chamber 70 at the right hand ends thereof (Figure 2) so that this passage will not be closed by movement of either element 45 or piston 64 until they reach the extreme right end of their strokes.

25 Positioned longitudinally within the chamber 75 is a plunger 94 a portion of which extends exteriorly of the body 24 so that the plunger may be moved manually. If the plunger is moved a sufficient distance to the left piston 72 and piston assembly 63 may be maintained in their respective positions as shown regardless of fluid pressures occurring within the fuse during experimental procedures, that is during bleeding operations or for overriding the fuse for any reason.

With a preferred embodiment of the hydraulic fuse thus generally described the function of the various parts and operation thereof will become apparent from the following description.

Operation.

In considering the operation of a fuse of the type disclosed it should be borne in mind that it is utilized to arrest the flow of fluid to a hydraulic actuator of the neutral leakage type. Accordingly there is an equal and continuous flow of fluid through each of the passages 82 and 83 during normal operations of the system. This flow may vary depending upon the demand of the actuator 11. Although the fuse is shown and disclosed in connection with an aircraft hydraulic system it may be used in any hydraulic system in which there is a continuous and equal flow of fluid through the system with which it is utilized.

For purposes of illustration it may be assumed that a hydraulic medium is supplied to the fuse at an initial pressure P_1 of 3000 p. s. i. and returned to the fuse at a pressure P_3 of 500 p. s. i. As the diameter of outlets 27 and 29, passageways 82 and 83, apertures 80, poppet valves 77 are all identical, respectively, and the springs 81 are properly selected the rate of flow from passages 82 and 83 will be equal as long as there is no failure (leakage) in pressure or return lines 20 or 21. As the rate of flow is the same from passages 82 and 83 equal pressure drops will occur at apertures 80 during normal operation of the system. In other words the difference between P_1 and P_2 will be equal to the difference between P_3 and P_4 during normal operations.

As the fuse is purged of air hydraulic fluid fills the various chambers and passages formed therein. Fluid fills bore 35 and freely flows past the body portion of valve element 38 to fill counterbore 43. Chambers 69 and 70 will be filled by means of passages 82 and 89, respectively. Accordingly chamber 69 and the left side of piston 64 will be subject to pressure P_1 while chamber 70 and the right side of piston 64 will be subject to pressure P_2 . Fluid will also flow to the closed end of bore 37 via passage 93 also subjecting this portion of bore 37 to pressure P_2 . Fluid from inlet 28 enters chambers 67 and 75 via passages 83 and 92, respectively, subjecting these chambers to pressure P_3 . Fluid at a pressure P_4 fills chamber 74 via passage 91.

With fluid pressure acting on each end of valve element 38 and element 45 the spring 49 exerts sufficient force to maintain the assembly (valve element 38 and element 45) in the position shown in Figure 2. The valve element 38 and element 45 will remain in the relative position just described as long as the rate of fluid flow from passages 82 and 83 remains equal. Also the piston assembly 63 and piston 72 will remain in their relative position shown in the Figure 2. This is due to the fact that pressures P_1 , P_2 , P_3 and P_4 acting on pistons 64 and 72 cancel each other and the only effective force remaining is that of the spring 49.

Should a failure occur at A in one of the pressure lines 20 (Figure 1) the rate of flow from passage 82 will increase. In the event of such a failure the flow from passage 83 may remain constant, decrease a certain amount or be completely discontinued depending on the nature of the above failure. As the flow of fluid increases from passage 82 a greater pressure drop will occur between that in passage 82 and outlet 27 than originally existed. At the same time the pressure drop occurring between the fluid pressure in passage 83 and outlet 29 may remain the same, decrease, or become zero. Accordingly the fluid pressure acting on pistons 64 and 72 will become unbalanced and the resulting fluid pressure will move these pistons to the right at such time as the resultant fluid pressure overcomes the force of spring 73. After the piston assembly 63 has moved to the right a predetermined distance the reduced portion

68 of rod 65 will extend on each side of shoulder 60 to effectively vent chamber 70 and bore 37 (to the right of element 45) to chamber 74. Accordingly the pressure P_1 acting on the left ends of valve element 38 and element 45, plus the small force exerted by spring 50, will force hydraulic fluid from bore 37 (to the right of element 45) and cause valve element 38 to firmly seat itself on seat 34 precluding the flow of pressure fluid to passage 88 and in turn to line 20 where the fracture occurred. Since flow through the unit has been blocked the pressures throughout the unit downstream of valve seat 34 will equalize and pistons 64 and 72 will be returned to the position shown in Figure 2 by spring 73. At such time as the pump 22 is no longer operating the system pressure P_1 returns to atmospheric or a low pressure it will be apparent that valve element 38 and element 45 will be returned to the position shown in Figure 2 by the spring 49.

The pressure drop which occurs as fluid flows past the poppets 77 is graphically represented in Figure 3. In this figure the curve CDEF illustrates the fluid pressure drop which will occur according to the quantity of fluid flowing through the system. The portion CD indicating the pressure drop prior to the time that poppets 77 are unseated, the portion DE indicating the pressure drop from the time the poppets are unseated until they bottom on elements 84, and the portion EF indicating the pressure drop after the poppets have bottomed. The slope of the straight line portion DE of the curve is determined by the force exerted by springs 81 and prevents the pressure drop from becoming excessive throughout the normal range of flow through the system.

In the present embodiment the portion DE of the curve CDEF represents flow through the system at such times as the valve element of the actuator 11 is moved from its neutral position, in other words at such times as control surfaces are being moved during a maneuver of the plane 10. Accordingly the flow of fluid through the system throughout the major portion of its operation is represented by the portion CD of the curve. Here a very small difference in fluid flow will produce a large pressure drop to overcome the force of spring 73. Accordingly the fuse will be extremely sensitive easily detecting fluid leaks of small magnitude. Although the fuse will not be as sensitive when operating in the range represented by the portion DE of the curve CDEF severe leakage will be detected at this time. A severe fluid leak will cause the flow through passage 82 to fall within the portion EF of the curve. Fluid leaks of small magnitude, occurring but not detected during the time the system is operating in the range represented by the portion DE of the curve, will be detected as soon as the system returns to the range represented by the portion CD of the curve. Accordingly small fluid leakages will be detected immediately upon the completion of a maneuver of the plane if not before.

The manner in which the fuse functions to arrest the flow of fluid to actuator 11 in the event of a rupture in one of the pressure lines 20 has been described above. Should a failure occur in a return line 21 the action of the fuse will be similar and should be apparent to one skilled in the art. In this instance the rate of flow from passage 83 will be less than normal resulting in a less pressure differential between P_3 and P_4 than originally existed. Accordingly the equilibrium of fluid pressures acting on piston assembly 63 and piston 72 will be disturbed, a resultant fluid pressure exceeding the force exerted by spring 73 will result causing assembly 63 and piston 72 to move to the right. The component parts of the fuse will now function in a similar manner as described above in connection with a failure in pressure line 20.

Should a cavitation occur in the fluid system, at any time the system is subject to system pressure, a surge condition will result as the cavity is refilled with fluid.

Such a condition will cause a temporary increase in the rate of flow from passage 82 accompanied by an increased pressure drop between that in passage 82 and outlet 27. If it was not for the restrictor 90 such a condition, regardless of the length of its duration, would cause the fuse to function to arrest fluid flow to the actuator 11. Under all conditions, as the piston 64 moves to the right, fluid in escaping from chamber 70 must flow through restrictor 90 in passage 89 prior to the time that it becomes vented to return pressure by the reduced portion 68 of rod 65. The size of the aperture in restrictor 90 is selected according to the estimated time necessary to fill a cavity as described above, a time delay of perhaps two seconds will elapse before the valve assembly 63 has moved far enough to the right to vent chamber 70 and bore 37 to return pressure. After a surge of fluid (lasting two seconds or any predetermined time) the rate of flow from passage 82 will return to normal, hydraulic equilibrium will be reestablished with respect to piston assembly 63 and piston 72, and spring 73 will return the assembly 63 and piston 72 to their normal position (shown in Figure 2).

While in order to comply with the statute, the invention has been described in language more or less specific as to structural features, it is to be understood that the invention is not limited to the specific features shown, but that the means and construction herein disclosed comprises a preferred form of putting the invention into effect, and the invention is therefore claimed in any of its forms or modifications within the legitimate and valid scope of the appended claims.

What is claimed is:

1. A hydraulic system of the closed circuit type and in which fluid continuously circulates during the operation thereof: said system including a pressurized fluid source, a fluid actuator, and a fuse comprising a housing portions of which define first and second fluid passages extending therethrough; predetermined portions of said passages being of identical configuration in extent and cross-section; conduit means connected to provide fluid communication between said housing, fluid source, and actuator so that fluid in circulating through said system passes sequentially through said first passage, actuator, second passage, and fluid source; a restrictor positioned in each of the identical portions of said passages adapted to effect fluid pressure drops as fluid flows therethrough; valve means in said first passage responsive to said pressure drops whereby said valve means allows fluid flow through said first passage when said pressure drops effected by said restrictors are equal and arrests fluid flow through said first passage when said pressure drops effected by said restrictors are unequal.

2. A hydraulic system of the closed circuit type and in which fluid continuously circulates during the operation thereof: said system including a pressurized fluid source, a fluid actuator, and a fuse comprising a housing portions of which define first and second fluid passages extending therethrough; predetermined portions of said passages being of identical configuration in extent and cross-section; conduit means connected to provide fluid communication between said housing, fluid source, and actuator so that fluid in circulating through said system passes sequentially through said first passage, actuator, second passage, and fluid source; a valve assembly having opposed end portions in said first passage movable between a first position allowing fluid flow and a second position arresting fluid flow therethrough; fluid in said first passage together with fluid diverted from said first passage and resilient means exerting a combined pressure on one end portion of said valve assembly to maintain the latter in said first position thereof during normal operations of said system; fluid diverted from said first passage exerting pressure on the other end portion of said valve assembly tending to move the latter to said second position thereof during normal operations of said

system; restrictor means located in each of the identical portions of said passages adapted to effect equal and unequal pressure drops at such times as there is equal and unequal fluid flow, respectively, through said passages; and piston means in said housing responsive to said pressure drops and functioning to release fluid exerting pressure on said other end portion of said valve subsequently after said pressure drops become unequal.

3. A hydraulic system as set forth in claim 2: further characterized by said restrictor means comprising movable valve elements; a valve seat in each of said passages; resilient means urging said valve elements into seating engagement with said valve seats at such times as the fluid pressure in said passages does not exceed a predetermined amount; fluid under pressure in said passages adapted to move said valve elements off said valve seats at such times as the fluid pressure therein exceeds said predetermined amount; and apertures in said valve elements permitting fluid flow through said passages when said valve elements are seated on said valve seats.

4. A hydraulic system as set forth in claim 2: further characterized by including restrictor means delaying the release of fluid, exerting pressures on said other end portion of said valve, for a predetermined interval of time after said pressure drops become unequal.

5. A hydraulic fuse comprising: a housing portions of which define a first chamber therein; a valve seat dividing said chamber into first and second sub-chambers; a valve in said first sub-chamber movable between seated and unseated positions with respect to said seat; a first piston in said second sub-chamber dividing the latter into first and second compartments; resilient means normally acting to maintain said valve in said unseated position and said valve and piston in abutting relation; portions of said housing defining a second chamber therein; a partition having an aperture therein dividing said second chamber into high and low pressure fluid chambers; a piston assembly comprising a piston and piston rod operationally mounted in said high pressure fluid chamber; a second piston operationally mounted in said low pressure fluid chamber; an end portion of said piston rod extending through said aperture to alternately provide a fluid by-pass and a fluid tight seal between adjacent ends of said high and low pressure fluid chambers according to operational positions of said piston assembly; resilient means normally acting to maintain said piston assembly in a position in which said piston rod provides said fluid tight seal and maintains said end portion of said piston rod and said second piston in abutting relation during all operational positions of said assembly and second piston; a first fluid passage extending between an exterior surface of said housing and said first sub-chamber; a second fluid passage extending between an exterior surface of said housing and said first compartment; said first and second passages and said first chamber defining a high pressure fluid passage when said valve is in said unseated position; a low pressure fluid passage extending between non-adjacent exterior surfaces of said housing; identical fluid restrictors located in said high and low pressure fluid passages; unidirectional fluid flow occurring through said high and low pressure fluid passages during the operation of said fuse, the fluid entering said high pressure passage via said first passage; a fluid passage extending between said high pressure chamber at the end thereof spaced from said partition and said high pressure passage upstream with respect to said restrictor located therein; a fluid passage extending between said high pressure chamber at the end thereof adjacent said partition and said high pressure passage downstream with respect to said restrictor located therein; a passage extending between said second compartment at the end thereof most removed from said valve seat and said high pressure chamber at the end thereof adjacent said partition; a passage extend-

ing between the low pressure chamber at the end thereof spaced from said partition and said low pressure passage up-stream with respect to said restrictor located therein; and a fluid passage extending between said low pressure chamber at the end thereof adjacent said partition and said low pressure passage downstream with respect to said restrictor located therein.

6. A hydraulic fuse as set forth in claim 5: further characterized by including a fluid restrictor positioned in said fluid passage extending between said high pressure 10

chamber at the end thereof adjacent said partition and said high pressure passage downstream with respect to said restrictor located therein.
